UNITED STATES PATENT OFFICE.

EDWIN E. BARNEY, OF SYRACUSE, NEW YORK, ASSIGNOR TO UNION TYPEWRITER COMPANY, OF JERSEY CITY, NEW JERSEY, A CORPORATION OF NEW JERSEY.

TYPE-WRITING MACHINE.

No. 902,519.

Specification of Letters Patent.

Patented Oct. 27, 1908.

Original application filed June 11, 1900, Serial No. 19,889. Divided and this application filed May 13, 1908.
Serial No. 432,556.

To all whom it may concern:

Be it known that I, EDWIN E. BARNEY, citizen of the United States, and resident of Syracuse, in the county of Onondaga, and 5 State of New York, have invented certain new and useful Improvements in Type-Writing Machines, of which the following is a specification.

My invention relates to typewriting machines and more particularly to case shifting mechanism, and the object of said invention is to provide a simple and efficient mechanism of the character specified.

To the above and other ends which will 10 herein after appear, my invention consists in the features of construction, arrangements of parts and combinations of devices to be hereinafter described, and particularly pointed out in the appended claims.

20 In the accompanying drawings, wherein like reference characters indicate corresponding parts in the various views, Figure 1 is a detail side elevation of sufficient number of parts of one form of typewriting machine to 25 illustrate my invention in its embodiment therein; the parts being shown in the normal position in this view. Fig. 2 is a like view of the same showing the disposition of the parts when they have been shifted for upper 30 case writing.

The present case is a division of my application Serial No. 19,889, filed June 11th, 1900.

While the case shifting mechanism of my invention may be applied to various styles of 35 typewriting machines, I have shown the invention embodied in the present instance in a front-strike typewriting machine of the character disclosed in my Patent No. 594,978, dated December 7th, 1897, wherein both the 40 platen and printing instrumentalities are shifted towards and away from each other to change the case position of the parts for upper and lower case writing.

The frame 1 of the machine is provided 45 with upright standards 2 and 3 and a transverse bar 4. Bell crank key levers 5 are pivoted to the transverse bar 4 at different elevations, as indicated by the positions of the pivots 6, the upper end of each key lever 50 being connected to a link 7 which in turn is pivotally connected to the heel of the associated type bar 8. The type bars are segmentally arranged and are each pivoted at 9 to a hanger secured to a type bar segment

or quadrant 10. A cylindrical rotative 55 platen 11 is provided with a platen shaft 12 which turns in bearings in a suitable platen frame or carrier which in the present instance comprises arms or plates 13 situated at each end of the platen and rigidly connected together by suitable tie rods. The platen frame is pivotally connected by the platen shaft with rearwardly extending parallel links or arms 15 which in turn are pivoted at 16 to a truck section 17 suitably 60 guided and supported for movement from side to side of the machine; a guide rod 18 constituting one of the supports for the truck. The lower forwardly extending ends of the arms or end plates 13 are united by a cross 70 bar 20 which carries a grooved roller or grooved rollers 21 which bear upon a shift rail or rod 22. This shift rod 22 is secured to arms 23 secured to a rock shaft 24 and extending therefrom at an inclination downward and toward the rear. The shaft 24 is mounted in suitable bearings in the standards 3 and provided with upwardly and forwardly directed extensions or arms 25 pivoted at 26 to the upwardly extending 80 projections 27 carried by the type bar segment 10 so that diverging arms 23 and 25 respectively carry the platen and type bar segment. One of the lower arms 23 is extended to form a stop member 28 movable 85 between shoulders or stops that preferably consist of adjustable screws 29 and 30 which are received in threaded openings in lugs 31 forming part of a fixed piece which is secured to the main frame 1 of the machine. 90 These screw stops 29 and 30 limit the movement of the member 28 and the parts controlled thereby. The arm 23 which carries the extension 28 is connected through a toggle or knuckle joint to the shift key, said toggle comprising a toggle link 32 pivoted at 33 to the arm 23 and the opposite end of this link is pivoted at 34 to a companion toggle link 35 and to an upwardly and forwardly extending actuating link 36. The 106 lower end of the toggle link 35 is pivoted at 37 to a fixed bracket 38 so that the toggle joint comprising the two links 32 and 35 is connected at one end to one of the arms 23 and at the other end to a fixed point. The forward end of the actuating link 36 is pivoted at 39 to an upwardly directed arm 40 of a bell crank shift lever 41 provided

with a shift key 41^a, said key lever being pivoted to one of the pivot rods 6 carried by the transverse bar 4 of the frame. A contractile spring 42 is connected at one end 5 43 to the actuating link 36 and is connected at its opposite end to a pin 44 projecting from one of the upright standards 3. Fig. 1 shows the normal disposition of the parts. When the relation of the parts is to be 10 changed for upper case writing the operator will depress the shift key 41^a, thereby pulling forward on the actuating link 36 to break the toggle from the substantially straight line position shown in Fig. 1 and to 15 move the parts against the tension of the spring 42 to the positions shown in Fig. 2. The effect of depressing the shift key is to move the diverging arms 23 and 25 in opposite directions, the depending arms 23 20 moving forwardly until the member 28 contacts with the lower screw stop 30. This movement of the arms 23 moves the shift rail in an inclined path downwardly and forwardly around the rock shaft 24 as a 25 center, thereby shifting the platen downwardly and forwardly on the links 15 around the pivots 16. At the same time the arms 25 are moved upwardly and rearwardly carrying the type bar segment 10 upwardly 30 and rearwardly towards the platen.

I have provided means for retaining the parts in their shifted positions, such means comprising a locking lever or member 45 pivoted at 46 to a fixed portion of the machine 35 and having a finger piece or key 47 by which the lever may be actuated. This lever also has a depending arm 48 with a locking notch or recess 49 formed therein. A locking pin 50 projects laterally from the arm 40 of the 40 shift key lever 41 into the path of the depending arm 48 of the locking lever. The relation of the parts is such that an upward movement of the locking lever 45 around its pivot is effective to bring the depending arm 45 48 thereof into engagement with the locking pin 50 and to actuate the shifting lever 41 and the case shifting mechanism controlled thereby. As the locking lever 45 and shift key lever 41 move from their normal positions 50 around their respective pivots 46 and 6, the portions 49 and 50 move in arcs which intersect with each other so that at the completion of the shifting movement the portions 49 and 50 may be brought into engagement and the 55 levers 41 and 45 are interlocked to lock the parts in their shifted positions, it being understood that the pin 50 bears against a shoulder formed by the depression or recess 49 in the locking lever to prevent the parts from 60 moving back to normal position. In order to release the parts so that they may be restored to the normal positions, it is merely necessary to depress the locking lever 45 which effects a disengagement of the locking 65 members 49 and 50 from each other and the

spring 42 will restore the parts to normal position.

From the foregoing description it will be seen that the shift is effected through a flexing connection comprising the pivotally connected links 32 and 35 of the shift mechanism, which links constitute toggle links arranged end to end and that said links in the normal position of the parts shown in Fig. 1 are approximately in a straight line position, 70 and that the toggle is flexed or broken from this position to shift the shiftable members so that the links constitute what may be termed a reverse toggle, and that the spring 42 acts to counterbalance the weight of the 75 platen or the shifted part and to restore the shifting mechanism to normal position. By this construction I am enabled to provide simple and efficient case shifting mechanism in which the initial resistance opposed to the 80 actuation of the shift key or keys is reduced to a minimum. 85

The shift key 41^a is in the nature of a temporary shift key, the parts resuming their 90 normal positions when pressure on said key is released, whereas, the shift key 47 is in the nature of a permanent shift key which may be actuated to shift the parts and maintain them in the shifted position until the key is 95 unlocked or released.

Various changes may be made without departing from the spirit and scope of the invention.

What I claim as new and desire to secure by Letters Patent, is:—

1. A typewriting machine comprising a quadrant and type-bars mounted thereon, an impression platen, a lever for simultaneously shifting the quadrant and platen with relation to each other, and an independently movable locking lever, said levers having shoulders movable in intersecting arcs and adapted to interlock at the point of intersection for holding the quadrant and platen in their adjusted positions.

2. A typewriting machine comprising a quadrant and type-bars mounted thereon, a carriage, an impression platen mounted on the carriage, a lever for shifting the quadrant and platen with relation to each other, and an independently movable locking lever for engaging and rocking the former lever and holding the quadrant and platen in their adjusted positions.

3. In a typewriting machine, the combination of a quadrant and type-bars mounted thereon, a carriage having an independently movable frame, a platen supported by the frame, a lever for simultaneously shifting the quadrant and frame in opposite directions, and an independently movable locking lever for engaging and rocking the former lever, said levers having shoulders adapted to interlock to hold the quadrant and frame in their shifted positions.

4. In a typewriting machine, the combination of a quadrant and type-bars mounted thereon, an impression platen, and means provided with a toggle-joint for simultaneously shifting the quadrant and platen with relation to each other. 5
5. In a typewriting machine, the combination of a quadrant and type-bars mounted thereon, a movable frame carrying an impression platen and means provided with a toggle-joint for shifting the quadrant and frame in opposite directions. 10
6. In a typewriting machine, the combination of a quadrant and type-bars mounted thereon, a carriage, an impression platen mounted on the carriage, and means provided with a toggle-joint for shifting the quadrant and platen in opposite directions. 15
7. In a typewriting machine, the combination of a quadrant and type-bars mounted thereon, an impression platen, means provided with a toggle-joint for shifting the quadrant and platen, and a locking member for engaging said means and holding the same in one of its adjusted positions. 20
8. In a typewriting machine, the combination of a quadrant and type-bars mounted thereon, a carriage having an independently movable frame, an impression platen mounted on the frame, means provided with a toggle-joint for shifting the quadrant and frame, and a locking member for engaging said means and holding the quadrant and frame in their shifted positions. 25
9. In a typewriting machine, the combination with a quadrant and type-bars mounted thereon, of a carriage having an independently movable frame, an impression platen mounted on the frame, means provided with a toggle-joint for shifting the quadrant and frame in opposite directions, and adjustable stops for limiting the movement of said means. 30
10. A typewriting machine comprising a quadrant and type-bars mounted thereon, an impression platen, means for shifting the quadrant and platen with relation to each other, adjustable stops for limiting the movement of said means, and a locking member for engaging said means and holding the same in one of its adjusted positions. 35
11. In a typewriting machine, the combination with a quadrant and type-bars mounted thereon, a carriage having an independently movable frame, an impression platen supported by the frame, and means for shifting the quadrant and platen in opposite directions, of adjustable stops for limiting the movement of said means, and a locking member for engaging said means and holding the quadrant and frame in their shifted positions. 40
12. A typewriting machine comprising a quadrant and type-bars mounted thereon, an impression platen, a rock shaft provided 45
- with diverging arms connected respectively to the quadrant and to the platen, adjustable stop-shoulders for engaging one of the arms for limiting their rocking movement, a toggle-joint connected to one of the arms, 70 and a shift-lever connected to said toggle-joint.
13. In a typewriting machine, the combination with a quadrant and type-bars mounted thereon, an impression platen and its carrier, of a rock-shaft provided with diverging arms connected to the quadrant and platen carrier, adjustable stops for engaging one of the arms, and means provided with a toggle-joint connected to one of the 80 arms for rocking said arms and shifting the quadrant and platen-carrier. 75
14. A typewriting machine comprising a quadrant and type-bars mounted thereon, an impression platen, a rock-shaft having diverging arms for supporting the quadrant and platen, adjustable stop-shoulders for engaging one of said arms, a shift-lever connected to one of the arms for actuating the same, and a locking member movable into 85 engagement with the shift-lever for holding the same in one of its adjusted positions. 90
15. In a typewriting machine, the combination with a quadrant and type-bars mounted thereon, an impression platen and its carrier, of a rock-shaft having upwardly and downwardly extending arms for supporting the quadrant and carrier, adjustable shoulders for engaging the lower arm, a shift-lever connected to one of the arms for shifting the quadrant and carrier, and a locking member movable into engagement with the shift-lever for holding the same in one of its adjusted positions. 95
16. In a typewriting machine comprising a quadrant and type-bars mounted thereon, an impression platen, a shift-lever connected to the quadrant and platen for shifting the same with relation to each other, said shift-lever being provided with an engaging shoulder, and a lock-lever provided with a shoulder, said shoulders being movable in intersecting arcs and adapted to interlock with each other at substantially the point of intersection of said arcs. 100
17. In a typewriting machine, the combination with a quadrant and type-bars mounted thereon, a carriage, an impression platen and its carrier, of a shift-lever connected to the quadrant and carrier for shifting the same in opposite directions, the shift-lever being provided with a shoulder, and a lock-lever provided with an engaging shoulder, said shoulders being movable in intersecting arcs and adapted to interlock with each other at substantially the point of intersection of said arcs. 115
18. A typewriting machine comprising a quadrant and type-bars mounted thereon, an impression platen, a rock-shaft provided 120
- 125
- 130

with diverging arms for supporting the quadrant and platen, adjustable stop-shoulders engaging opposite faces of one of said arms, a toggle-joint having one end fixed 5 and its other end connected to one of the arms of the rock-shaft, a shift-lever connected to the knuckle of the toggle-joint and provided with an engaging shoulder, and a lock-lever provided with an engaging shoulder, 10 said engaging shoulders being movable in intersecting arcs and adapted to interlock with each other at substantially the point of intersection.

19. A typewriting machine comprising a 15 quadrant and type-bars mounted thereon, a carriage, an impression platen and its carrier mounted on the carriage, a rock-shaft having an upwardly extending arm connected to the quadrant and a downwardly 20 extending arm provided with a track for supporting the platen carrier, a shift-lever connected to the lower arm and provided with a shoulder, adjustable stops for limiting the movement of the rock-arms, and a 25 lock-lever having an engaging shoulder, said shoulders being movable in intersecting arcs and adapted to interlock at substantially the point of intersection.

20. In a typewriting machine, the combination of a rock shaft having two arms, a 30 track on one of the arms, a rocking carriage movable along the track and rocking with the arm to which the track is secured, a type-bar support connected to the other arm and 35 actuated thereby, a key lever connected to the arm to which the track is secured for rocking the arms and thereby moving the type-bar support and platen toward and from each other, and a movable hand actuated device coöperating with said key lever 40 for moving it and for automatically locking the same in one of its adjusted positions.

21. In a typewriting machine, the combination of opposed stop shoulders, two rock 45 arms having a common axis and extended in opposite directions from said axis, one of the arms extending between the stop shoul-

ders, a track secured to said one of the arms, a carriage riding on the track and rocking therewith, a platen on the carriage, a type-bar support pivoted to the other arm and actuated thereby, and a key lever connected to the arm to which the track is secured for rocking both arms and moving the type bar support and platen towards and from each 55 other.

22. In a typewriting machine, the combination of a platen, printing instrumentalities, and means for effecting a relative shift between said platen and printing instrumentalities transversely of the printing line for upper and lower case writing, and which comprises toggle links and key actuated means for actuating said toggle links to effect such case shift. 60

23. The combination with the shifting member of a typewriting machine, of a shift key, and an operative connection between the key and said member comprising two pivotally connected links which, on the 70 action of the shift key, act as a reverse toggle to thereby effect the shifting of said member.

24. The combination with the shifting member of a writing machine, of a flexing connection comprising two pivotally connected links arranged end to end and means 75 for flexing the links as a reverse toggle to effect a shifting of said member.

25. The combination with the shifting member of a writing machine, of a flexing 80 connection comprising two pivotally connected links arranged end to end and means for flexing the links as a reverse toggle to effect a shifting of said member, and a spring for counterbalancing the weight of 85 the shifting member.

Signed at Syracuse in the county of Onondaga and State of New York this 7th day of May A. D. 1908.

EDWIN E. BARNEY.
